ATTORNEY

UNITED STATES PATENT OFFICE

ALBERT A. BROWNSTEIN, OF WALNUT PARK, CALIFORNIA

NECKBAND CONSTRUCTION

Application filed October 20, 1928. Serial No. 313,744.

The present invention relates to the manufacture of shirts, and particularly to the method of attaching the front collar-button to the neck-band of a shirt on which a separate collar is used.

It is the present practice to provide in the neck-band of such shirts front and rear collar-button openings, the rear collar-button being attached to the neck-band, which latter is so constructed, as by the double thickening of the band material, that the collar-button cannot come directly in contact with the neck of the wearer, but is covered by an inner thickness of material.

The broad principle of the invention consists in the provision of means adapted for connection to the neck-band in proximity to the front buttonhole for preventing the collar-button coming into direct contact with the neck of the user.

A further object of the invention is to provide an attachment of the character described which is adapted for connection to the neck-bands of shirts having collars attached or not attached.

Another object of the invention is to provide a neck-band assembly in which the band is formed with the usual front collar-button opening and wherein a pocket for the reception of the base of the collar-button is formed by stitching a piece of material to the rear of the collar-band in proximity to the button-hole, so that the collar-button cannot come in direct contact with the neck of the wearer of the shirt.

Another object of the invention is to provide a neck-band attachment either in the form of a semi-closed pocket or in the form of a closed pocket, in which an opening or slit is provided in the wall thereof for the introduction of the head and shank of the collar-button, and wherein the material defining the slit, upon the introduction of the collar-button, will close over the base of the collar-button and be disposed between the button base and the neck of the wearer.

A further object of the invention is to provide a shirt-band attachment which is adapted to receive the collar-button from the top, side, bottom or rear of the same, means being

provided, regardless of from what point the button is inserted, for preventing the same from contacting with the neck of the wearer.

It is further specified that the nature of this invention and its peculiar construction adapts it to manufacture and sale as a new article of manufacture and to be readily and easily applied to shirts.

The invention is capable of receiving a variety of modified expressions, a few of which are shown on the accompanying drawings, but it is to be expressly understood that the drawings are for the purpose of illustration only and are not to be construed as a definition of the limits of the invention, reference being had to the appended claims for that purpose.

In the drawings:

Fig. 1 is a perspective view illustrating the application of the invention to the neck-band of a shirt, and in which the collar-button is inserted through the outer open end of the collar-band attachment.

Fig. 2 is a fragmental perspective view of a shirt illustrating a modified form of the invention attached to the collar-band in such manner, that the collar-button is inserted at the top edge of the neck-band.

Fig. 3 is a fragmental perspective view of a shirt and illustrating another modification in which the attachment of the invention to the rear of the collar-band is shown and likewise the inner end opening for the introduction of the collar-button.

Fig. 4 is a similar view illustrating a further modification in which the lower opening of the collar-band attachment is open for the introduction of the collar-button.

Fig. 5 illustrates a fragmental perspective view of a still further modification in which the attachment is formed with a slot or opening adapted for the introduction therethrough of a collar-button, the head of which projects through the front opening in the ordinary shirt-band.

In the views, 5 designates a shirt around the collar opening of which is stitched in the ordinary manner a collar-band 6, and in this instance only, the collar-button openings 7

and 8 in the confronting ends of the collar-band are shown.

The attachment comprising the present invention, as illustrated in Fig. 2, consists of a piece of material 9, adapted to be stitched along three of its sides to the rear surface of collar or neck-band 6 adjacent the buttonhole 7, so as to form an opening 10 for the introduction therethrough of the collar-button 11.

The piece of material 9 is of the same relative width of the collar-band 6 and the pleat 12 of the shirt, as clearly illustrated in Fig. 2. The stitching of the piece of material 9 to the collar-band 6 forms a pocket 13 rearwardly of the buttonhole 7 at the end of the collar-band immediately above the pleat 12, and the stitching operation to form the pockets, defines the various collar-button openings, as illustrated in Figs. 1 to 4, inclusive. The stitching to form the pockets in these forms may be indicated generally by the numeral 14 and in reverting to Fig. 1 it will be seen that the piece of material 9 has been stitched to the collar-band 6 at the upper, lower and inner edges to provide a front button receiving opening 15. In the form illustrated in Fig. 2, the cloth piece 9 is stitched to the collar-band along the sides and bottom to provide the opening 10 at the top for the introduction of the collar-button to the pocket 13.

In Fig. 3 the piece of material 9 is stitched at the top, bottom and outer end to the corresponding portions of the neck-band and consequently an inner collar-button opening 16 is provided, while in Fig. 4 the top and both ends are stitched to the inner part of the collar-band, which forms a lower collar-button opening 17.

In the forms illustrated in Figs. 1 to 4 inclusive, the base of the collar-button, when disposed within any of the pockets, will engage and be supported upon the inner surface of the cloth piece 9 and is thus prevented from contacting with the neck of the wearer of the shirt. Likewise, resultant of the different placement of the stitching in the various forms described, entrance for the collar-button may be had from the top, ends or bottom of the collar-button pocket, as desired.

In the modification illustrated in Fig. 5, the cloth piece 9 is stitched adjacent all of its edges to the collar-band 6 and is provided with a slit 18 disposed at right angles to and crossing the buttonhole, through which the collar-button is passed from the rear, the head and shank of the collar-button being extended through the usual collar-band opening 7. In this form, upon the introduction of the collar-button through the slit 18, the material 9 defining the slit due to its inherent elasticity holds the walls of the slit together, so that the base of the collar-button will rest thereupon and cannot engage the neck of the wearer.

The mode of attachment and use is as follows:

To the neck-band of an ordinary shirt without a collar may be attached by stitching a piece of material to form a pocket and the placement of such stitching will define differently located openings for the insertion of a collar-button. The collar-button upon insertion and location within the pocket so formed, has its head and shank projected through the usual collar-button opening in the band, while its base is disposed flat against the inner surface of the material forming the pocket. Thus, the base of the collar-button is prevented from engaging the neck of the wearer of the shirt and likewise, the collar-button is held in axial alinement with the buttonhole of the neck-band.

In the modification illustrated in Fig. 5, the collar-button is introduced into the pocket between the confronting surfaces of the collar-band and the attached material, through the slit formed in the latter, whereupon the material defining the slit is drawn together and thus presents a semi-united surface against which the base of the collar-button will rest. In this manner, the base of the collar-button is likewise prevented from engaging the neck of the wearer.

I claim as my invention:

1. As a new article of manufacture, a collar-band for shirts having a buttonhole adjacent one end thereof and a piece of material stitched along its edges to the rear surface of said collar-band forming a pocket and having a slit disposed at right angles to and crossing said buttonhole.

2. As a new article of manufacture, a collar-band having a buttonhole and a piece of material stitched along its edges to said collar-band and having a slit formed therein at right angles to said buttonhole and crossing it to permit the passage therethrough of a collar-button so that the base thereof will rest upon a semi-united surface of said material.

In testimony whereof, I have hereunto set my hand at Los Angeles, California, this 12th day of October, 1928.

ALBERT A. BROWNSTEIN.
